Primary Examiner — Rosemary K Tarcza

(57) **CLAIM**

The ornamental design for a battery pack, as shown and described.

DESCRIPTION

1. Battery pack

1.1 : Perspective

1.2 : Front

1.3 : Back

1.4 : Left

1.5 : Right

1.6 : Top

1.7 : Bottom

1. Title of the design#battery pack: 2. The battery pack is used for providing electrical energy; 3. Design 1 claim the shape of the front of the battery pack. 4. The most representative drawing or photograph is the perspective view of design 1.5. Design 1 is deemed as the base design.

1 Claim, 7 Drawing Sheets
